UNITED STATES PATENT OFFICE.

ALFRED W. STOEKLEY, OF PHILADELPHIA, PENNSYLVANIA.

DESIGN FOR A SKIRT-PROTECTOR.

SPECIFICATION forming part of Design No. 33,321, dated October 2, 1900.

Application filed August 28, 1900. Serial No. 28,360. Term of patent 14 years.

To all whom it may concern:

Be it known that I, ALFRED W. STOEKLEY, a citizen of the United States, residing at Philadelphia, in the county of Philadelphia and State of Pennsylvania, (whose post-office address is 2040 Howard street, Philadelphia,) have invented and produced a new and original Design for Skirt-Protectors, of which the following is a specification, reference being had to the accompanying drawing, forming part thereof.

The drawing represents my new and original design for a skirt-protector.

The skirt-protector has a knitted heading A, of undulating filling-threads *a*, forming wavy lines or bars running parallel to one another, and also having in addition to the wavy lines a series of rows of chain-stitches *b*, which extend longitudinally of the heading and tie the filling-threads, so that in general aspect the filling-threads run from chain-stitch to chain-stitch, producing a zigzag effect. The brush B consists of knitted tufts *c*, composed of threads doubled on themselves, the doubled ends *d* passing up into the marginal loops or

interstices formed by the undulating filling or inlay threads, where they are bound by the chain-threads.

The leading or material feature of the design is a skirt-protector composed of a knitted heading consisting of an inlay of thread or threads and chain-stitches, the thread or threads running from chain-stitch to chain-stitch in zigzag effect, and of a brush composed of threads doubled on themselves, the doubled ends extending up into and binding with the heading. 30 35

Having described my invention, what I claim as new, and desire to secure by Letters Patent, is—

The design for a skirt-protector substantially as herein shown and described. 40

In testimony whereof I have hereunto signed my name in the presence of two subscribing witnesses.

ALFRED W. STOEKLEY.
